BASE SUPPORT FOR CLAMP TYPE FOOD GRINDER OR SIMILAR ARTICLE

Ralph M. Marcantonio, Easton, Conn.

Application March 22, 1950, Serial No. 8,680

Term of patent 14 years

(Cl. D44—8)

To all whom it may concern:

Be it known that I, Ralph M. Marcantonio, a citizen of the United States, residing at Easton, county of Fairfield, State of Connecticut, have invented a new, original, and ornamental Design for a Base Support for Clamp Type Food Grinder or Similar Article, of which the following is a specification, reference being had to the accompanying drawing, forming a part hereof.

Fig. 1 is a top plan view of a base support for clamp type food grinder or similar article, showing my new design;

Fig. 2 is a side elevation thereof, and

Fig. 3 is an end view looking from the left of Fig. 2.

I claim:

The ornamental design for a base support for clamp type food grinder or similar article, substantially as shown.

RALPH M. MARCANTONIO.
